UNITED STATES PATENT OFFICE.

FRANK RUDOLPHI, OF CHICAGO, ILLINOIS, ASSIGNOR TO AMERICAN CAN COMPANY, OF NEW YORK, N. Y., A CORPORATION OF NEW JERSEY.

METHOD OF CUTTING CAN-HEADS OR OTHER SHEET-METAL BLANKS.

No. 922,194.

Specification of Letters Patent.

Patented May 18, 1909.

Application filed January 18, 1908. Serial No. 410,484.

To all whom it may concern:

Be it known that I, FRANK RUDOLPHI, a citizen of the United States, residing in Chicago, in the county of Cook and State of Illinois, have invented a new and useful Improvement in Methods of Cutting Can-Heads or other Sheet-Metal Blanks, of which the following is a specification.

My invention relates to the cutting of can heads or other sheet metal blanks from tin plate or other sheets by gangs of dies.

The object of my invention is to provide a method or process by which can heads or other blanks may be cut from sheets by gangs of dies economically or with a minimum quantity of waste material between the can heads or blanks and at the margins of the sheet, and in which one and the same press or gang of dies may be used for making the several successive cuts. To accomplish this result, the can heads or blanks are cut from the sheet in a staggered arrangement in three successive cuts, one third of the blanks at each stroke by gangs of dies arranged in odd numbered groups or multiples thereof, the sheet being reversed end for end between the first and second strokes or cuts and slipped or adjusted lengthwise for the third cut.

Figure 1 is a plan view representing a sheet after the first cut or stroke of an odd numbered gang or group of staggered dies, three in number. Fig. 2 represents the same sheet after it has been turned end for end and received the second cut from the same odd numbered group or gang of staggered dies. Fig. 3 represents the same sheet after it has been slipped or adjusted lengthwise and received the third cut from the same odd numbered gang or group of staggered dies. Fig. 4 represents a sheet after it has received the first, second and third cuts from a gang of dies containing a multiple or four of such odd numbered groups of dies. Fig. 5 represents a gang or group of odd numbered staggered dies.

In the drawing, A represents a gang of odd numbered staggered dies, which, for convenience, I have illustrated as being composed of three dies.

B represents a sheet from which can heads or other circular blanks are to be cut. The circles 1 represent the can heads or

blanks cut from the sheet by the first stroke. After the first stroke, the sheet B is turned end for end and placed under the same gang of dies A and the can heads or blanks 2—2—2 therefrom at the second stroke. Then the sheet is slipped or adjusted lengthwise and at the third stroke of the press, the remaining three heads or blanks 3—3—3 are cut therefrom. By this means, all the can heads or blanks may be cut from the sheet on three successive strokes of one and the same press, an equal number of blanks being cut at each stroke of the press.

The group or gang of dies may be composed of any odd number or of any multiple of any odd number. For example, in Fig. 4 of the drawing, I have illustrated a sheet as cut by a multiple of four times three or twelve dies, the same constituting in fact four adjacent odd numbered gangs or groups of three each.

I claim:

1. The method of cutting can heads or other blanks from metal or other sheets consisting in cutting an equal number of blanks at three successive strokes of an odd numbered group or gang of dies in staggered arrangement, reversing the sheet between the first and second strokes and adjusting it lengthwise between the second and third strokes said first, second and third cuts being each and all made by successive strokes of one and the same gang of staggered dies, substantially as specified.

2. The method of cutting can heads or other blanks from metal or other sheets in staggered arrangement from one and the same gang of dies, consisting in first cutting one third of the blanks in staggered arrangement from the sheet, then reversing the sheet and cutting a second third of the blanks from the sheet by a second stroke of the same gang of dies and then adjusting the sheet and cutting the remaining third of blanks from the sheet by a third stroke of the same gang of dies, an equal number of blanks being cut at each stroke, substantially as specified.

3. The method of cutting can heads or other blanks from metal or other sheets in staggered arrangement from one and the same gang of dies, consisting in first cutting one third of the blanks in staggered arrangement

ment from the sheet, then reversing the sheet and cutting a second third of the blanks from the sheet by a second stroke of the same gang of dies and then adjusting the sheet and cutting the remaining third of blanks from the sheet by a third stroke of the same gang of dies, an equal number of blanks being cut

at each stroke, the number of blanks cut at each stroke being either an odd number or a multiple thereof, substantially as specified. 10

FRANK RUDOLPHI.
